UNITED STATES PATENT OFFICE.

WALTER F. TESCHAN, OF MILWAUKEE, WISCONSIN.

CONCRETE-DISTRIBUTING MACHINE.

1,268,643.

Specification of Letters Patent. Patented June 4, 1918.

Application filed November 27, 1917. Serial No. 204,158.

To all whom it may concern:

Be it known that I, WALTER F. TESCHAN, a citizen of the United States, and resident of Milwaukee, in the county of Milwaukee, 5 and State of Wisconsin, have invented new and useful Improvements in Concrete-Distributing Machines, of which the following is a description, reference being had to the accompanying drawings, which are a part 10 of this specification.

The invention relates to concrete handling apparatus.

The invention is more particularly designed to provide a concrete distributing mechanism of the boom and bucket type with simple and efficient mechanism for dumping the bucket at different positions on the boom and then restoring the bucket to operative position for receiving a charge 20 from the concrete mixer. Devices of this kind are particularly adapted for laying concrete road the boom being capable of swinging laterally and the bucket being movable to different positions along the boom so 25 that the concrete may be distributed over a large area without changing the position of the mixer.

The invention further consists in the several features hereinafter set forth.

30 In the drawings:

Figure 1 is an elevation view of the device embodying the invention showing it in connection with the concrete mixer, the bucket being shown in dotted lines in discharging 35 position;

Fig. 2 is a section taken on the line 2—2 of Fig. 1;

Fig. 3 is a detail plan view of the bucket and the rear end of the boom;

40 Fig. 4 is a detail view of the tripping mechanism of the bucket, showing it in position just before the operation is completed.

In the drawings, the numeral 6 represents the frame of the mixer, 7 the mixing drum, 45 8 the discharge trough for the mixer, and 9 the boom as a whole, said boom being capable of swinging laterally and vertically.

The boom 9 consists of a pair of spaced apart connected together channel bars 10 50 forming a trackway. At their rear ends these bars carry brackets 11 through which a pivot pin 12, carried by a member 13, passes so that the boom may be raised and lowered in a vertical plane. The member 55 13 extends upwardly and is connected to a turntable 14 carried by the frame 6 so that

the boom may be swung in a horizontal plane. Means are provided for raising and lowering the boom consisting of a hand-operated winch 15 provided with a rope 16 60 which extends back to a pulley (not shown) carried by the frame of the machine and thence extends downwardly at 17 and is connected to a clevis 18 pivotally secured at its end adjacent the outer side of the channel 65 bars.

A carriage 19 is provided with a pair of flanged wheels 20 which are mounted upon the track way formed by the channel bars 10, and a dumpable bucket 21 is secured to 70 said carriage by brackets 22 and 23.

The bucket 21 is of the openable bottom type provided with bottom doors 24 pivotally secured at their outer side edges to the adjacent sides of the bucket, the sides of the 75 bucket being inclined toward the bottom to facilitate the discharge of material therefrom.

The doors of the bucket are held closed by means of a bail 25 secured at its ends to the 80 inner edges of the doors and intermediate their ends to the depending curved end of a link 26 which is pivotally secured to a crank 27 mounted on a shaft 28 pivotally mounted in the carriage 19. The arrangement of the 85 bail 25, link 26 and crank 27 is such that when the shaft 28 is rotated to swing the link 26 and crank 27 to the right and over dead center, as shown in Fig. 1, the doors are held closed by their own weight 90 and by the weight of the material within the bucket as the linkage is locked against movement. When the shaft is rotated to swing the link 26 and crank 27 to the left over dead center, the weight of the load will 95 open the doors of the bucket to discharge the load. The bucket may be manually opened and closed by a hand lever 29 mounted on the shaft 28. A stop 27' limits the forward movement of the crank 27.

100 The carriage is moved in or out along the boom by means of a cable 30 which is actuated by any suitable power means (not shown). This cable is connected at one end 31 to the carriage 17 and thence passes over a guide pulley 32 and upwardly over a drum (not shown) which is driven by suitable power and thence passes downwardly over a pulley 33 from there through an opening 34 in the carriage, thence around a pulley 35 110 mounted at the forward end of the boom and is secured at its other end 36 to the carriage.

The means for automatically dumping the bucket in any position upon the boom comprises means for rotating the shaft 28 to throw the linkage for the doors of the bucket over dead center to open the doors when desired. This consists of a two-part crank member comprising a crank 37 secured to the shaft 28 and a trip arm or lever 38 pivotally secured to said crank by a pin 39 and 5 yieldingly held against movement by a coiled spring 40 mounted on the pin 39 and having its ends 41 and 42 crossed, the end 41 yieldingly bearing upon a projection 43 on the lever 38 and the end 42 yieldingly bearing 10 upon a projection 44 on the crank 37. The lever 38 has a beveled end 45 which may frictionally engage the bottom side of one of the channel bars 10 or which may engage projections 46 on the boom formed by bolts 20 spaced a predetermined distance apart. With this construction as the carriage is moved forwardly along the boom the lever 38 rides along the under surface of the boom, the lever 38 and crank 37 being inclined 25 backwardly as shown in Fig. 1, and the lever 38 rides over the projections 46 on the boom because of the yielding connection with the arm 37. When the carriage and bucket have been moved to the desired position on the 30 boom and the bucket is moved backwardly the lever 38 engages the first projection 46 it comes in contact with and on a further backward movement of the carriage the lever 38 moves inwardly moving the crank 35 37 downwardly thereby turning the shaft 28 to throw the link 26 over dead center as shown in Fig. 4, after which the weight of the load opens the doors of the bucket and the linkage assumes the position shown in 40 dotted lines in Fig. 1.

The means for restoring the bucket to operative position consists of means for throwing the door opening and closing linkage over dead center on a reversal of the carriage and consists of the lever 29 which carries a roller 47 that engages a cam 48 carried by the boom and throws the linkage back to load receiving position before the carriage reaches the end of its rearward 50 travel upon the boom. The weight of the lever 29 is counterbalanced by a coiled spring 49 secured at one end to the shaft 28 and at its other end to the carriage 19.

With the foregoing construction the concrete after mixture is discharged through 55 the trough 8 into the bucket 21 and the bucket moved out along the boom to the desired place of deposit. On the backward movement of the carriage the tripping mechanism above described opens the doors of the bucket to discharge the load and the empty bucket is then moved inwardly upon the boom and the doors are closed before it reaches its charging position and while it 60 is in charging position the doors are held 65

closed because of the arrangement of the linkage.

It will be noted that the trip means for discharging the bucket is entirely independent of the cable and any other means besides the cable could be used to move the carriage along the boom. 70

I am aware that the details of the construction herein shown and described are capable of some modification and change 75 and I therefore desire it to be understood that such changes in construction as come within the scope of the appended claims, I deem to be within the spirit of my invention. 80

What I claim as my invention is:

1. In a concrete distributing apparatus, the combination, with a boom and a carriage movable back and forth along the same, of a dumpable bucket carried by the carriage, and means inoperable on the forward movement of the carriage and engaging the boom on the backward movement of the carriage to dump said bucket. 85

2. In a concrete distributing apparatus, 90 the combination, with a boom and a carriage movable back and forth along the same, of a bottom dump bucket provided with dumping doors, of door-operating means mounted on the carriage for opening and closing said doors, and trip means inoperable on the forward movement of the carriage and for said door-operating means engaging the boom on the backward movement of the carriage to move said door operating-means to 95 open said doors. 100

3. In a concrete distributing apparatus, the combination, with a boom and a carriage movable back and forth along the same, of a bottom dump bucket, means for opening 105 and closing the bottom of said bucket, including a rotatable shaft, and automatic trip means, for turning said shaft to discharge the bucket, inoperable on the forward movement of the carriage and operable by 110 engagement with the boom on the backward movement of the carriage. 115

4. In a concrete distributing apparatus, the combination, with a boom and a carriage movable back and forth along the same, of a bottom dump bucket, means for opening and closing the bottom of said bucket including a rotatable shaft, and automatic trip means including a two-part 120 crank arm carried by said shaft, the parts of said crank being movable with respect to each other, one part of said crank engaging the boom on the backward movement of the carriage to turn said shaft to discharge the bucket. 125

5. In a concrete distributing apparatus, the combination with a boom and a carriage movable back and forth along the same, of a bottom dump bucket, means for opening and closing the bottom of said bucket in- 130

- cluding a rotatable shaft, and automatic trip means comprising a two-part crank arm carried by said shaft, the parts of said crank arm being yieldingly pivotally connected together, one part of said crank engaging the boom on the backward movement of the carriage to turn said shaft to discharge the bucket.
6. In a concrete distributing machine, the combination, with a boom and a carriage movable back and forth along the same, of a bucket provided with dumping bottom doors, door operating means comprising a shaft, a crank and linkage connecting said crank with said doors, and automatic trip means for the door operating means comprising a crank secured to said shaft, an arm yieldingly pivotally connected to said crank and adapted to engage the boom to trip the door operating means to discharge the bucket.
7. In a concrete distributing machine, the combination, with a boom and a carriage movable back and forth along the same, of a bucket provided with dumping doors, door operating means comprising a shaft, a crank, and linkage connecting said crank with said doors, automatic trip means inoperable on the forward movement of the carriage and engaging the boom on the rearward movement of the carriage for opening said doors, and means for automatically closing the doors.

In testimony whereof, I affix my signature.

WALTER F. TESCHAN.
